US0D1014250S

(12) **United States Design Patent** (10) **Patent No.:** **US D1,014,250 S**
(45) **Date of Patent:** **** Feb. 13, 2024**

(54) **CAP**

(71) Applicants: **Trilliant Food and Nutrition, LLC**, Little Chute, WI (US); **Horseshoe Beverage Company, LLC**, Neenah, WI (US)

(72) Inventors: **Brian Roffers**, Freedom, WI (US); **Brian Thon**, Appleton, WI (US); **Shaylyn Wulderk**, Greenville, WI (US)

(73) Assignees: **Trilliant Food and Nutrition, LLC**, Little Chute, WI (US); **Horseshoe Beverage Company, LLC**, Neenah, WI (US)

(**) Term: **15 Years**

(21) Appl. No.: **29/808,726**

(22) Filed: **Sep. 22, 2021**

(51) **LOC (14) Cl.** **09-07**

(52) **U.S. Cl.**

USPC **D9/443; D9/454**

(58) **Field of Classification Search**

USPC D7/392.1, 396.2; D9/434-436, 444, 454, D9/499, 443

CPC A47G 19/2272; A47G 19/22; B65D 43/00; B65D 43/02; B65D 47/08

(57) **CLAIM**

The ornamental design for a cap, as shown and described.

DESCRIPTION

FIG. 1 is a top perspective view of the cap;

FIG. 2 is a bottom perspective view thereof;

FIG. 3 is a front elevation view thereof, the right, left, and rear elevation views being substantially the same as the front elevation view;

FIG. 4 is a top plan view thereof; and,

FIG. 5 is a bottom plan view thereof.

The broken lines depict portions of the cap in which the design is embodied that are not considered part of the claimed design.

1 Claim, 5 Drawing Sheets
